UNITED STATES PATENT OFFICE.

LEONARD W. CROSS, OF WHEELING, WEST VIRGINIA, ASSIGNOR TO CONSOLIDATED EXPANDED METAL COMPANIES, OF BRADDOCK, PENNSYLVANIA, A CORPORATION OF PENNSYLVANIA.

METAL LATH.

Application filed October 12, 1926. Serial No. 141,074.

This invention relates to metal lath, that is to say, it relates to that class of expanded metal which is made of relatively light gauge metal expanded substantially by deploying, 5 in contradistinction to the heavier grades of expanded metal made on the guillotine machines.

As an example of a deploying machine for expanding metal fabric, I refer to the 10 Salmon and Booton Patent No. 1,408,647, issued March 7, 1922, which shows a machine of the divergent guide type, and in connection with which my invention is primarily useful.

15 One of the primary objects of my invention is to make it possible to make smaller diamond metal lath on a machine such, for example, as the divergent guide machine above referred to.

20 It is another object of the invention to produce metal lath which is relatively stiff and strong in those regions where stiffness and strength are required, and which is relatively light.

25 Still another object of the invention is to provide sheets of metal lath which, considered as a whole, are relatively stiff, although composed of relatively light stock.

30 More specifically it is an object of the invention to overcome certain difficulties in expanding the metal which will be more particularly hereinafter set forth.

I obtain the foregoing, together with such other objects and advantages as may herein- 35 after appear, or are incident to my invention, by means of the blank and the lath illustrated in the preferred form in the accompanying drawings, wherein—

Fig. 1 is a plan view of a fragment of a 40 blank suitable for carrying out one form of my invention,

Fig. 2 is a plan view of a fragment of a sheet of metal lath made from the blank of Fig. 1, Fig. 2, however, being drawn on an 45 enlarged scale, and

Fig. 3 is a view similar to Fig. 1 but showing the spacing of the slits of the blank greatly exaggerated transversely of the sheet for purposes of illustration.

50 Referring now to the blank of Figs. 1 and 3, the reference character A denotes the blank as a whole. This blank is provided with staggered rows of slits 7 and 8 to provide,

in the finished product, the strands 9 and connecting bridges 10. On examination of 55 these figures it will be seen that the rows of slits for a distance inwardly from the longitudinal edge B of the sheet are more widely spaced from one another than they are toward the middle portion of the sheet or blank. 60 This provides strands and bridges for a longitudinally extending section of the lath which are wider than the remaining strands and bridges. The longitudinal section of the sheet of lath which is composed of these relatively wider strands and connecting bridges is, therefore, stiffer and stronger than the remaining portion of the sheet. It is to be understood that the rows of slits along each longitudinal edge portion of the blank are 65 made more wide, as above described, so that there is this stiff strong section along each edge portion of the sheet extending lengthwise thereof.

Before the blank passes through the expanding machine, the outermost strands or salvage portions at each edge are deformed somewhat as indicated at 11, so that the pins of the pin wheels 12, such as illustrated in the aforesaid patent, will properly engage 80 the blank.

One of the important advantages of the foregoing is that I am enabled to make a commercially satisfactory product on such a machine from heavier stock than would otherwise be the case. If blanks of heavy stock, slotted in the ordinary fashion, are expanded on a machine of this general character, there is apt to be a pulling out or breakage or distortion at the edge portions of the sheet 90 which is detrimental, not only from the standpoint of the finished product, but also from the standpoint of cost of manufacture because of the heavy losses involved. Therefore, it has been customary to make a 95 larger diamond metal lath when using a heavy stock to avoid breakage in the machine at the edges. By my invention I am able to make small diamond metal lath from heavy stock. By the same token I am enabled to produce a 100 smaller diamond metal lath for any given weight or grade of stock than was possible heretofore.

Another advantage of the foregoing arrangement is that besides adding general 105 stiffness to the sheet as a whole, the sheet is

strong where it overlaps the adjoining sheet and also where it is to be nailed to the wood-work or studding. Thus, by my invention I can secure adequate strength for nailing or 5 support, while still using a very light gauge metal.

I claim:

1. Metal lath having a number of its strands and connecting bridges, from a longitudinal edge of the sheet inward, wider than the remaining strands and bridges whereby the sheet has a relatively stiff and strong section longitudinally and marginally thereof.
- 10 2. A blank for lath adapted to be expanded in an expanding machine of the divergent guide type comprising a metal sheet having rows of slits staggered transversely of the sheets to provide the strands and connecting

bridges of the finished product, the rows of 20 slits for a distance inward from a longitudinal edge of the blank being more widely spaced than the other rows.

3. A blank for lath comprising a metal sheet having rows of slits staggered transversely of the sheets to provide the strands and connecting bridges of the finished product, the rows of slits for a distance inward from a longitudinal edge of the blank being 25 more widely spaced than the other rows.

4. Metal lath having certain of its strands and bridges lengthwise of the sheet wider than the remaining strands and bridges to provide a relatively stiff and strong mesh-work section running lengthwise of the sheet. 30

In testimony whereof, I have hereunto signed my name.

LEONARD W. CROSS.
